UNITED STATES PATENT OFFICE.

JOHN NELSON SPIES, OF WATERTOWN, NEW YORK.

COIN-HOLDING CARD.

SPECIFICATION forming part of Letters Patent No. 673,299, dated April 30, 1901.

Application filed December 15, 1900. Serial No. 40,046. (No model.)

To all whom it may concern:

Be it known that I, JOHN NELSON SPIES, a citizen of the United States, residing at Watertown, in the county of Jefferson and State 5 of New York, have invented certain new and useful Improvements in Coin-Holding Cards; and I do declare the following to be a full, clear, and exact description of the invention, such as will enable others skilled in the art to 10 which it appertains to make and use the same, reference being had to the accompanying drawings, and to the letters of reference marked thereon, which form a part of this specification.

15 This invention relates to new and useful improvements in coin-holding cards, and especially to the provision of a card having a series of apertures of various sizes corresponding to the outline of various coins to receive 20 the coins, said cards being preferably of a thickness equal to or greater than the thickness of the coins to avoid their detection when sent through the mails, and the provision of means for retaining the coins in place in the 25 apertures, consisting of flexible strips which form a portion of the card and extending across the apertures and slightly beyond the margins of the latter.

The invention is clearly illustrated in the 30 accompanying drawings, which, with the letters of reference marked thereon, form a part of this application, and in which drawings similar letters of reference indicate like parts throughout the several views, in which— 35 Figure 1 is a plan view of my improved coin-holding card. Fig. 2 is a central longitudinal section through the card, and Fig. 3 is an enlarged detail view showing one of the flexible coin-holding straps slightly sprung 40 out.

Reference now being had to the details of the drawings by letter, A designates a card, made, preferably, of cardboard, having a series of oval recesses B cut therein, said recesses or apertures being arranged in pairs

and of different sizes, the outer curved margins of each pair of apertures being in the arc of the same circle and each pair being of such a size as to correspond with the size of a particular coin which is to be held in the card ; 5 by the curved walls of said apertures. Separating each pair of recesses is a flexible strip C, forming a part of the cardboard, and in order to make said strips sufficiently flexible to hold the coin in place and to make room 55 to receive the coin each strip or strap C extends beyond the marginal edges of the recesses on either side, as shown, so that the strap may spring out beyond the face of the card at the ends of the apertures, as plainly 60 shown in the detail view in the drawings.

To the under surface of the card is secured a paper D, covering the apertures and forming a bottom on which the coins may rest.

In applying the coin or placing same in the 65 apertures the strap is sprung out and the coin slipped under same, and the curved outlines of the apertures will hold the coin from a lateral play, while the flexible strap will serve to hold the coin from movement in the opposite 70 direction.

Having thus described my invention, what I claim to be new, and desire to secure by Letters Patent, is—

A coin-holding card, having a series of recesses arranged in pairs, the curved margins of each pair of recesses being on the arc of the same circle, flexible straps between each pair of recesses integral with the card, and extending beyond the opposite ends of the 80 recesses, and alternately arranged in parallel rows, with their inner ends adjacent to the longitudinal median line of the board, as set forth.

In testimony whereof I affix my signature 85 in presence of two witnesses.

JOHN NELSON SPIES.
